CLAIM

The ornamental design for a blood processing machine, as shown and described.

DESCRIPTION

FIG. 1 is a perspective view showing the front and right side of the blood processing machine;

FIG. 2 is a front elevational view of the blood processing machine shown in FIG. 1;

FIG. 3 is a right side elevational view of the blood processing machine shown in FIG. 1 of which the left side is a mirror image;

FIG. 4 is a rear elevational view thereof;

FIG. 5 is a top plan view thereof; and,

FIG. 6 is a front and right side perspective view thereof, with the centrifuge access door shown in open position.
